UNITED STATES PATENT OFFICE.

LUIGI VIEZZI, OF JERSEY CITY, NEW JERSEY.

FIRE-ESCAPE.

1,194,098.

Specification of Letters Patent.

Patented Aug. 8, 1916.

Application filed May 31, 1913, Serial No. 770,925. Renewed February 9, 1916. Serial No. 77,300.

To all whom it may concern:

Be it known that I, LUIGI VIEZZI, a citizen of the United States and a resident of Jersey City, in the county of Hudson and State of New Jersey, have invented a new and Improved Fire-Escape, of which the following is a full, clear, and exact description.

My invention relates to fire escapes and it has for its object to provide a main spiral chute spaced from the ground and having an auxiliary chute adapted to slide on the main chute and form a continuation thereof for connecting the main chute with the ground, means being provided for automatically releasing the auxiliary chute so that it may descend by gravity to the ground on the opening of a door leading to the main chute, and means also being provided for sounding an alarm as the auxiliary chute descends.

Additional objects of my invention will appear in the following complete specification, in which the preferred form of the invention is disclosed.

25 In the drawings similar characters of reference indicate corresponding parts in all the views, in which—

Figure 1 is an elevation of a building provided with my fire escape; showing the auxiliary chute in lowered position. Fig. 2 is a transverse section of Fig. 1, showing the auxiliary chute in raised position; Fig. 3 is a fragmentary view showing the construction of the auxiliary chute; Fig. 4 is a transverse sectional view of the main chute; Fig. 5 is a fragmentary view showing the means by which the auxiliary chute is freed automatically on the opening of the doors; and Fig. 6 is a transverse sectional view of a modified form of the main chute.

40 By referring to the drawings it will be seen that a standard 5 is provided, which is supported by the horizontal members 6, which are secured to the building 7. The main spiral chute 8 is supported by the horizontal members 6, there being members 9 which are secured to and depend from the horizontal members 6, these depending members 9 being secured to the side of the main chute 8.

Mounted to slide on the main spiral chute 8 there is an auxiliary chute 10, the auxiliary chute 10 having flanges 11, which extend over the top of the main spiral chute 8.

55 This auxiliary spiral chute 10 is connected

with a bearing 12, by members 13, this bearing 12 being mounted for rotating on the standard 5.

Secured to the side of the building there is a bracket 14, to which is secured a bell 15, this bell being connected by a stud 16 with a friction wheel 17, the friction wheel 17 bearing against the outer side of the auxiliary chute 10 so that when the auxiliary chute rotates and descends relatively to the main chute 8, the friction wheel 17 will be rotated to operate the bell 15 and sound an alarm.

Journaled in bearings in the horizontal members 6 there is a rock shaft 18, an arm 19 being secured to the rock shaft 18, this arm 19 being adapted to be disposed under a flange 20 on the bearing 12, for supporting the said bearing and the auxiliary spiral chute 10. There are also a plurality of arms 21 which are secured to the rock shaft 18, links 22 being articulated to the arms 21 and having laterally extending eyes 23 through which pass the links 24, the links 24 having eyes 25 through which the links 22 extend. The links 24 are connected to doors 26, so that when any one of the doors 26 is opened it will draw inwardly the link 24 secured to the door and also the link 22 connected therewith to rock the shaft 18 by means of an arm 21. As the shaft is rocked, the arm 19 is moved away from the flange 20 on the bearings 12, as shown in the dotted lines in Fig. 5 of the drawings, thereby freeing the bearings 12 so that the said bearings and the auxiliary spiral chute may descend to connect the main spiral chute 8 with the ground, the friction wheel, which is in contact with the auxiliary spiral chute sounding an alarm through the bell 15, as the auxiliary spiral chute descends.

By referring to Figs. 4 and 6 of the drawings it will be seen that the main chute 8 is constructed with a lining of asbestos material 8^a, which is disposed between the metal 100 inner and outer surfaces 8^b. The main spiral chute 8 has its top 8^c constructed with an elongated hood 8^d there being ventilating windows 8^e in the side of the hood 8^d. It will be understood that the main spiral chute 105 8 may be constructed as shown in Fig. 4 of the drawings, or, if desired, it may be constructed with its outer side at the bottom, rounded, as shown in Fig. 6 of the drawings.

Having thus described my invention I claim as new and desire to secure by Letters Patent:

- 5 1. In a fire escape a main spiral chute, an auxiliary chute telescoping with the main chute, a standard mounted axially relatively to the main chute, a bearing, mounted on the standard, and members connecting the bearing with the auxiliary chute. 50
- 10 2. In a fire escape a main spiral chute, an auxiliary chute slidably engaging the main chute, a standard mounted axially relatively to the main chute, a bearing, mounted on the standard, members connecting the bearing 55 with the auxiliary chute, and a member movable relatively to the bearing for engaging the bearing to support the auxiliary chute. 55
- 15 3. In a fire escape a main spiral chute, an auxiliary chute telescoping with the main chute, a standard mounted axially relatively to the main chute, a bearing mounted on the standard, members connecting the bearing with the auxiliary chute, a friction wheel engaging the auxiliary chute, and an alarm 60 adapted to be operated by the friction wheel. 65
- 20 4. In a fire escape a main spiral chute, an auxiliary chute slidably engaging the main chute, a standard mounted axially relatively to the main chute, a bearing mounted on the standard, members connecting the bearing 65 with the auxiliary chute, a rock shaft having an arm for engaging the bearing to support the auxiliary chute, and means to rock the shaft. 70
- 25 5. In a fire escape a main spiral chute, an auxiliary chute slidably engaging the main chute, a standard mounted axially relatively to the main chute, a bearing mounted on the standard, members connecting the bearing 75 with the auxiliary chute, a rock shaft having an arm for engaging the bearing to support the auxiliary chute, a door, and means connecting the door with the shaft for rocking the latter. 80
- 30 6. In a fire escape a main spiral chute, an auxiliary chute slidably engaging the main 85

chute, a standard mounted axially relatively to the main chute, a bearing mounted on the standard, members connecting the bearing with the auxiliary chute, a rock shaft, having an arm for engaging the bearing to support the auxiliary chute, a second arm secured to the rock shaft, a door, and telescopic means connecting the door with the second-mentioned arm for rocking the shaft when the door is moved in one direction but which permits the shaft to rock relatively to the door.

7. In a fire escape a main chute, an auxiliary chute slidably engaging the main chute, a rock shaft having means for supporting the auxiliary chute, a second arm secured to the rock shaft, and telescopic means connecting the door with the second-mentioned arm for rocking the shaft when the door is moved in one direction, but which permits the shaft to rock relatively to the door.

8. In a fire escape a main chute, an auxiliary chute slidably engaging the main chute, means for supporting the auxiliary chute relatively to the main chute, a door, and telescopic means connecting the door with the first-mentioned means for operating the first mentioned means when the door is moved, but permitting the first-mentioned means to operate relatively to the door.

9. In a fire escape a main chute, an auxiliary chute slidably engaging the main chute, means for supporting the auxiliary chute relatively to the main chute, a door, and means connecting the door with the first-mentioned means for operating the first-mentioned means, but permitting the first-mentioned means to operate relatively to the door.

In testimony whereof I have signed my name to this specification in the presence of two subscribing witnesses.

LUIGI VIEZZI.
